UNITED STATES PATENT OFFICE.

FRANKLIN M. SAWYER, OF KANSAS CITY, MISSOURI.

BABY-BED.

1,211,762.

Specification of Letters Patent. Patented Jan. 9, 1917.

Application filed December 18, 1914. Serial No. 877,966.

To all whom it may concern:

Be it known that I, FRANKLIN M. SAWYER, a citizen of the United States, residing at Kansas City, in the county of Jackson and State of Missouri, have invented certain new and useful Improvements in Baby-Beds, of which the following is a specification.

This invention relates to screened baby beds and has for its object to produce a bed of the character mentioned possessing a number of advantageous features of construction and organization of parts herein-after more particularly set forth.

To this end the invention consists in certain novel and peculiar features of construction and combination of parts as herein-after described and claimed, and in order that it may be fully understood reference is to be had to the accompanying drawings, in 20 which—

Figure 1, is a perspective view of a screened baby bed embodying my invention, the mattress being broken away to disclose features otherwise not clearly shown. Fig. 2, is a vertical transverse section of the bed. Fig. 3, is an enlarged horizontal section through one of the corner posts or legs and the adjacent portions of the side and end frames of the bed. Fig. 4, is a vertical section on the dotted line IV of Fig. 2, with the mattress omitted. Fig. 5, is a fragmentary view of a removable floor adapted to be supported just above the mattress.

Referring to the figures of the drawing in detail, 1 indicates four corner posts or legs and rigidly secured to and between each pair of transversely opposite legs is a rectangular frame 2 provided with vertical rods 3 which extend from the bottom to the top of the frame and to exclude flies and mosquitos from entering the bed at the ends said frames are covered at the outer sides of the rods by screens 4, the screens being preferably permanently secured to the frames.

In substantially the horizontal planes of the upper and lower ends of end frames 2, the corner posts or legs are provided at their inner sides with sockets 5. One of the end pair of legs is equipped with small wheels 6, for convenience in moving the bed about, it being understood that to move it the opposite end will be lifted slightly so as to bring the wheels into service.

Fitting between the longitudinally opposite posts of the end frames and of substantially the same height as the latter are

frames 7, provided with dowels or pins 8 for engagement in the sockets 5 of the posts, and to secure the side frames reliably to the posts they are provided with pivoted catches 9 for engagement with headed pins or screws 10 secured to the posts as shown clearly.

One of the side frames is provided for its full length with spaced rods 11 and said side is covered preferably by a single screen 12. The opposite side of the frame 7 is provided with a horizontal partition 13 extending from one end of said frame to the other, the partition being located a few inches above the bottom of said frame, and from the latter to the partition said side frame is provided with vertical spaced rods 14, and a screen 15 is secured to the frame at the outer side of said rods. The opening in said side frame constituted by the space above the partition 13, is adapted to be closed by a skeleton door 16 provided with rods 17 to extend from the upper to the lower side of the door, and said door is provided exteriorly with a screen 18. The door is hinged at its lower end at 19 to the partition bar 13 and is provided with a pair of catches 20 for engagement with keepers 21 secured to the top rail of said side frame.

The bed is provided with a slatted bottom 22 of the type shown or of any equivalent construction, and secured to and underlying the bottom are substantially U-shaped springs 23 having their lower or free ends bowed upwardly at 24 and adapted to fit snugly on the cross rods or hangers 25, the hangers being provided with vertical crank arms 26, which engage the lower rails of the side frames and thereby afford the proper support for the bottom 22.

For closing the top of the bed to exclude flies and mosquitos, I provide a folding hinged top, the top being of the folding type to permit the bed to be placed fairly close to a wall without necessitating shifting its position each time it is necessary or desirable to swing the top to closed or open position.

The top consists of two sections 27 hinged together at 28 and equipped with screens 29. One of the sections is provided with a handle or knob 30 and is also provided with hinge members 31 for connection with hinge members 32 secured to the top of the adjacent side frame. The top is adapted to rest upon the side and end frames and to open it, the handle or knob 30 will be pulled

upward, this action raising and moving rearward the hinged edges of the sections 27 and of course sliding the front edge of the front section along the tops of the end 5 frames. When the hinged section is vertical, the front section will fit flatly against it so that both sections may be swung together to a pendent position, at the side which constitutes the back of the bed.

10 For placing the child in or removing it from the bed, it being understood of course that the bed is provided with a mattress 33, the door 16 will be opened, as one may handle the child with less exertion through 15 said door opening than by reaching down over the top of the bed. Another advantage of the side door opening is that the bed can be drawn close to the mother's bed at night so that she can reach from her bed 20 into the baby's bed without rising to her feet.

The posts are provided at their inner sides in a level slightly lower preferably than the side door opening, with small supporting brackets 34 for the accommodation of a floor 35 upon which a child can conveniently amuse himself without necessitating attention from the mother. The 25 corners of the floor are cut away to accommodate the corner posts so that no openings shall be left at the margins of the floor through which small toys or other 30 objects might fall to the mattress below, from which position such objects could be recovered without removing the child and 35 raising the floor.

From the above description it will be apparent that I have produced a screened baby bed possessing features of advantage,

such as the protection of the child, the conversion of the bed into a convenient and protected play yard or room, and convenience for the mother in reaching from her bed to the child's at night through the side door opening of the baby's bed.

It will also be seen that the bed is of knock-down construction for convenience of storage and transportation.

It is to be understood that I reserve the right to make all changes falling within the 50 spirit and scope of the appended claim.

I claim:—

A baby bed, comprising ends, sides arranged between said ends, means connecting the ends and sides to prevent independent 55 movement in every direction except longitudinally of the sides, fastening devices connecting the ends and sides against movement longitudinally of the sides; one of the sides having an opening and an outwardly opening door controlling said opening, and a suitably supported bottom for the bed arranged between the sides and occupying a horizontal plane below the lower margin of said door opening, in combination with a movable top, and screens covering the ends, the top and the sides, the screen for the side provided with the door opening consisting of two sections, one covering the door and the other the side below 70 the door.

In testimony whereof, I affix my signature, in the presence of two witnesses.

FRANKLIN M. SAWYER.
